(57) **CLAIM**

The ornamental design for a cosmetic container and cap, substantially as shown and described.

DESCRIPTION

FIG. 1 is a top, front and right side perspective view of a first embodiment of a new design for a cosmetic container and cap;

FIG. 2 is a front elevation view of the container and cap shown in FIG. 1;

FIG. 3 is a rear elevation view of the container and cap shown in FIG. 1;

FIG. 4 is a right side elevation view of the container and cap shown in FIG. 1, a left side elevation view being a mirror image thereof;

FIG. 5 is a top plan view of the container and cap shown in FIG. 1;

FIG. 6 is a bottom plan view of the container and cap shown in FIG. 1;

FIG. 7 is a top, front and right side perspective view of a second embodiment of a new design for a cosmetic container and cap;

FIG. 8 is a front elevation view of the container and cap shown in FIG. 7;

FIG. 9 is a rear elevation view of the container and cap shown in FIG. 7;

FIG. 10 is a right side elevation view of the container and cap shown in FIG. 7, a left side elevation view being a mirror image thereof;

FIG. 11 is a top plan view of the container and cap shown in FIG. 7;

FIG. 12 is a bottom plan view of the container and cap shown in FIG. 7;

FIG. 13 is a top, front and right side perspective view of a third embodiment of a new design for a cosmetic container and cap;

FIG. 14 is a front elevation view of the container and cap shown in FIG. 13;

FIG. 15 is a rear elevation view of the container and cap shown in FIG. 13;

FIG. 16 is a right side elevation view of the container and cap shown in FIG. 13, a left side elevation view being a mirror image thereof;

FIG. 17 is a top plan view of the container and cap shown in FIG. 13; and,

FIG. 18 is a bottom plan view of the container and cap shown in FIG. 13.
